UNITED STATES PATENT OFFICE.

HENRY FREISTROFFER, OF FORT WAYNE, INDIANA.

DESIGN FOR A CALK.

SPECIFICATION forming part of Design No. 30,483, dated April 4, 1899.

Application filed March 11, 1899. Serial No. 708,767. Term of patent 14 years.

To all whom it may concern:

Be it known that I, HENRY FREISTROFFER, a citizen of the United States, residing at Fort Wayne, in the county of Allen and State of Indiana, have invented and produced a new and original Design for Calks, of which the following is a specification, reference being had to the accompanying drawing, forming part thereof.

10 The figure is a perspective showing the configuration of my new design.

As shown in the drawing, the leading or material feature of my design consists of the thickened portion A, gradually tapering to an 15 edge, and the curved flaring ribs B B, extending from the sides of the base.

C is an indentation made in the side of the calk.

Having described my invention, what I claim as new, and desire to secure by Letters 20 Patent, is—

The design for a calk, as herein shown and described.

In testimony whereof I affix my signature in presence of two witnesses.

HENRY FREISTROFFER.

Witnesses:

P. V. VOORHEES,
Wm. J. LENNORT.
